UNITED STATES PATENT OFFICE.

LESTER M. ILGENFRITZ, OF ORANGE, NEW JERSEY, ASSIGNOR TO AMERICAN TELEPHONE AND TELEGRAPH COMPANY, A CORPORATION OF NEW YORK.

ELIMINATION OF INTERFERENCE IN CARRIER SYSTEMS.

Application filed May 21, 1924. Serial No. 714,931.

To all whom it may concern:

Be it known that I, LESTER M. ILGENFRITZ, residing at Orange, in the county of Essex and State of New Jersey, have invented 5 certain Improvements in Elimination of Interference in Carrier Systems, of which the following is a specification.

This invention relates to carrier systems and more particularly to the elimination of 10 external interference in such systems.

In systems employing carrier frequencies for the transmission of signals, one of the 15 principal sources of external interference is due to radio transmitters employing frequencies lying within the range transmitted by a carrier channel. Such interference is produced by the line wires acting as an antenna to pick up the radiated wave and transmit it to the receiving carrier apparatus.

It has heretofore been proposed to overcome interference of this sort by picking up a component interfering wave and impressing it upon the circuit at some point 25 common to all of the carrier channels, with such phase and amplitude as to neutralize the interfering component transmitted over the line wires. Some difficulty has been found in applying this method, however, 30 because of the lack of stability of the balance obtained. This lack of stability may arise from changes in the frequencies of the interfering radio transmitters, from changes 35 in the propagation constant of the telephone line from temperature, humidity, etc., and changes in the propagation of the electromagnetic waves radiated from the radio transmitter due to the movements of clouds, etc.

Such changes are not controllable at the receiving carrier terminal and they are sufficient to displace the condition of balance in a very short period of time. In order to 45 avoid the necessity of having an attendant constantly supervising the system to keep it properly balanced, it is proposed, by the present invention, to effect an automatic control of the balance. More specifically, since the balance depends upon proper control of the balancing currents, both with 50 respect to the phase and magnitude, the invention involves means for indicating unbalance of phase and magnitude, together

with means for independently adjusting both the phase and the magnitude of the balancing currents in response to any indicated unbalance. 55

The invention may now be more fully understood from the following description when read in connection with the accompanying drawing, the figure of which illustrates a preferred embodiment thereof. 60

Referring to the drawing, ML designates a main transmission line of a carrier system, 65 which is connected through a hybrid coil comprising windings 10, 11 and 12 with terminal carrier apparatus TC, of any well known type, the carrier apparatus functioning to interconnect the common carrier transmission line ML with a plurality of terminal lines, such as TL₁, TL₂, and TL₃. 70

The interfering waves from a radio station will flow over the two sides of the main line ML in parallel, but due to the dissimilarity of the two sides of the lines 75 an unbalance component will result which tends to flow serially over the two sides of the line. The unbalance component of the radio waves will produce interference in the receiving channels of the carrier apparatus TC unless suitable measures are taken. By bridging an inductance element 13 across the conductors of the main line ML at the midpoints of the windings 10 and 11 of the hybrid coil and by taking a tap, such as 14, 80 from the midpoint of the bridge 13, the wave component flowing over the two sides of the line in parallel (which does not cause any interference) may be received in a suitable circuit and so translated as to neutralize the 85 interfering component which tends to flow serially over the line. 90

A filter F and an artificial line AL are included in circuit with the ground tap 14, the former being for the purpose of adjusting the phase and the latter for the purpose of adjusting the amplitude of the wave component which is to be used to balance the interfering wave component from the distant radio station. When the amplitude and phase of the wave component have been 95 adjusted the wave is transmitted over conductors 15 to the terminal carrier apparatus TC. It will be observed that the interfering wave is impressed upon the carrier apparatus through the winding 12 of the hybrid 100

coil so that if the balancing wave is of the same amplitude and is 180° out of phase with the interfering wave, the latter will be neutralized and will produce no effect upon 5 the carrier terminal TC.

In order to automatically maintain the proper balance of the balancing wave, a phase balancer PB is provided, comprising a double vacuum tube circuit wherein the 10 grids of both tubes are varied in potential at a phase difference of 180° by the voltage picked up from the ground tap 14 after being passed through the variable filter F acting as a phase adjuster and the variable 15 artificial line AL acting as an amplitude adjuster. The connection for this purpose is established through the input transformer 16. The interfering potential flowing serially over the line wires is impressed upon a 20 secondary winding 17, inductively related to the bridged inductance 13, and is applied through a transformer 18 to the grids in such manner as to produce potentials upon both grids which are in phase with each 25 other. The plates of both tubes are connected to a polarized relay 19 and the operation of the circuit will be such that a phase difference of 90° or 270° between the waves applied through transformers 16 and 18 30 will cause no movement of the relay armature. If, however, the phase difference becomes something other than 90° or 270° , the relay armature will move either one contact or the other to operate a motor controlling 35 apparatus MP for adjusting the filter F until the 90° or 270° phase condition is stored.

In order to obtain the quarter phase relation between the waves impressed through 40 transformers 16 and 18, a fixed phase shifting device 20 is included in the circuit between transformers 17 and 18, this device producing a 90° phase shift in the wave transmitted from 17 to 18. A switch 21 is 45 also provided, and by throwing this switch into either one of two positions the phase shift may be changed from 90° to 270° as desired.

In order to maintain the neutralizing 50 wave of the proper amplitude to balance out the interfering wave, the amplitude balancer AB is provided. This consists of a double detector circuit so arranged that one side of the detector circuit is connected to the source of interfering waves through a 55 transformer 22, while the other side of the detector circuit is connected to the balancing wave through a transformer 23. A polar relay 24 is provided in the output 60 circuit of the balanced detector arrangement and the rectified component from each detector tube flows through one of the windings of the polar relay. When the amplitude of the interfering wave is the same as 65 that of the balancing wave, equal and oppo-

site currents flow through the two windings of the polar relay 24 and its armature will remain in neutral position. If the amplitude of one of the waves is changed with respect to that of the other, an unbalancing 70 effect will be produced so that more current flows through one or the other of the two windings of the polar relay 24, and its armature is shifted in one direction or the other to operate the motor MA, which adjusts the 75 artificial line AL until the proper balance is obtained.

Further details of the apparatus will be clear from a description of the operation, 80 which is as follows: Let us assume that an induced potential from a radio source is impressed upon the two line wires of the line ML and flows over the two line wires in parallel, passing to ground through the two halves of the coil 13 and over the conductor 85 14. If the two sides of the main line ML were accurately balanced with respect to ground, no series component would result, but as this condition is not attained in practice a series component will flow over 90 the upper conductor of the line ML, through the left-hand half of the winding 10, through the inductance 13, through the left-hand half of the winding 11, and back over 95 the other side of the line ML. If the line ML is accurately balanced by the network N no current will flow in the network and consequently no interfering current will appear in the right-hand halves of the windings 10 and 11. The interfering potential 100 flowing over the line ML, as above described, passes through the transformer and into the terminal carrier apparatus TC.

The component of the induced wave 105 which flows to ground over the conductor 14 does not cause any interference but passes to ground through the first section of the wave filter F. A wave is accordingly propagated through the filter F and through 110 the artificial line AL, and thence over the conductors 15 to the terminal carrier apparatus TC. If the wave filter F and the artificial line AL are properly adjusted the amplitude of the wave component passing 115 through the circuit 15 will arrive at the terminals of the winding 12 with the same amplitude as the interfering component, but will be 180° out of phase with the interfering component so that the two effects will just balance and no interference will be produced in the terminal apparatus TC.

Let us suppose that the filter F is not 120 properly adjusted and that the interfering and balancing waves arrive at the terminals of the winding 12 in some other phase relation than 180° . The balancing wave will be impressed upon the input of the phase balancer PB through the transformer 16 and its phase relation at the transformer 16 125 will be the same as its phase relation at the 130

terminals of the winding 12. At the same time, a component corresponding to the interfering wave is impressed upon the secondary 17 and is transmitted through the 5 phase changer 20 and through the transformer 18 to the input circuit of the phase balancer. If the balancing wave and interfering wave are in phase, and the phase shifter device 20 were not present, the component 10 transmitted through the transformer 18 will be 180° out of phase with respect to the wave impressed upon the transformer 16. By passing through the phase shifter 20, however, its phase is displaced 90°, and 15 depending upon the setting of the switch 21, the interfering wave component transmitted from the winding 17 will shift at the transformer 18 either 90° or 270° out of phase with the component transmitted to the transformer 16.

The wave impressed through the transformer 16 produces opposite effects upon the grids of the two tubes, that is, effects that are 180° out of phase with each other. 25 The waves impressed through the transformer 18, however, produce similar effects upon both grids, that is, effects having the same phase relation. A consideration of the circuit arrangement of the phase balancer 30 PB shows that if the wave impressed through the transformer 18 is either in phase with the wave impressed through the transformer 16 or is 180° out of phase therewith, the two waves will have additive effects upon 35 the grid of one tube and opposing effects upon the grid of the other tube, so that the greatest possible condition of unbalance will obtain, and the armature of the polar relay 19 must be shifted to one contact or the other. On the other hand, if the wave impressed through the transformer 18 is either 40 90° or 270° out of phase with the wave impressed through the transformer 16, the resultant currents flowing in the two halves 45 of the output circuit will be equal and the armature of the relay 19 will remain in its neutral position. As soon as the displacement in the two waves becomes other than 90° or 270°, as the case may be, the current 50 flowing in one side of the circuit becomes greater than that flowing in the other side and the armature of the relay 19 moves to its upper or its lower position.

If the armature moves to its upper position 55 it closes a circuit of the relay 30, whereas if it moves to its lower position it closes a circuit of relay 31. Relay 30 completes the field and armature circuits of the motor MP to drive it in one direction and 60 relay 31 closes the circuits to drive the motor in the opposite direction. In either case, the motor will be driven in such a direction as to adjust the condensers of the filter F so that the wave impressed through the 65 transformer 16 will be brought back to quar-

ter phase relation with the wave impressed through the transformer 18, whereupon the condition of balance of the circuit PB will again result and the armature of the polar relay 19 will be in neutral position.

In order to take care of the amplitude of the balancing component a wave corresponding to the interfering component is transmitted through the winding 17, through the transformer 22 to the grid of the upper tube 75 of the amplitude balancer AB. At the same time, a wave corresponding to the balancing component is transmitted through the transformer 23 to the grid of the lower tube. Regardless of the phase relations of the two waves, if they are of the same amplitude 80 they will produce direct current components in the upper and lower windings of the polar relay 24, which are equal to each other, and the armature of the relay 24 will 85 remain in neutral position. If the amplitude of the interfering component decreases the current flow in the upper winding of the relay 24 decreases, the armature is shifted to its lower position, thereby closing the 90 circuit of the relay 32 so that the motor MA is driven in such a direction as to reduce the amplitude of the balancing wave until both waves again have the same amplitude, whereupon the armature of the relay 24 will swing 95 to its neutral position. If the amplitude of the balancing wave should be less than that of the interfering wave, a greater current will flow through the upper winding of the relay 24 so that the armature will shift to 100 its upper contact and close the circuit of the relay 33, which causes the motor MA to rotate in the opposite direction, thereby adjusting the artificial line AL to increase the transmission loss of the balancing wave until 105 its amplitude again equals that of the interfering wave, whereupon the armature of the relay 24 shifts to neutral position.

It should be noted that although the balancing wave is obtained from the same conductors of the line ML as the interfering wave, the two circuits are in effect separate and distinct circuits and a change in the attenuation of the series circuit does not necessarily produce a proportionate change in the 110 attenuation of the circuit over the two sides of the line in parallel to ground. Likewise, the change in the propagation constant of the telephone line proper does not produce a proportionate change in the propagation 115 constant of the circuit over the two sides of the line. Consequently, it will be apparent that a change in the phase or amplitude of the current flowing from winding 17 through the phase shifter 20 does not necessarily correspond to a similar and equal change in the phase or amplitude of the current flowing over the conductor 14. Hence, 120 it is necessary to automatically balance both with respect to phase and amplitude as 125 130

4
above described, unless the balance adjustment is to be performed manually.

It will be obvious that the general principles herein disclosed may be embodied in many other organizations widely different from those illustrated without departing from the spirit and scope of the invention as defined in the appended claims.

What is claimed is:

10 1. In combination with a transmission circuit subject to interfering waves, an arrangement to neutralize said interfering waves comprising means to pick up energy from the interfering source to produce balancing waves corresponding to the interfering wave, a phase controller and an amplitude controller for controlling the phase and amplitude of said balancing waves so that they may be impressed upon said transmission circuit equal in amplitude and opposite in phase to the interfering wave, and means automatically controlled by said interfering wave and said balancing wave to adjust said phase controller to maintain the waves 25 in opposite phase relation.

2. In combination with a transmission circuit subject to interfering waves, an arrangement to neutralize said interfering waves comprising means to pick up energy from the interfering source to produce balancing waves corresponding to the interfering wave, a phase controller and an amplitude controller for controlling the phase and amplitude of said balancing waves so that they may be impressed upon said transmission circuit equal in amplitude and opposite in phase to the interfering wave, and means automatically controlled by said interfering wave and said balancing wave to adjust said amplitude controller to maintain the amplitudes of the waves the same.

3. In combination with a transmission circuit subject to interfering waves, an arrangement to neutralize said interfering waves comprising means to pick up energy from the interfering source to produce balancing waves corresponding to the interfering wave, a phase controller and an amplitude controller for controlling the phase and amplitude of said balancing waves so that they may be impressed upon said transmission circuit equal in amplitude and opposite in phase to the interfering wave, means automatically controlled by said interfering wave and said balancing wave to adjust said phase controllers to maintain the waves in opposite phase relation, and means automatically controlled by said interfering wave and said balancing wave to adjust said amplitude controller to maintain the amplitudes of the waves the same.

4. In combination with a transmission circuit subject to interfering waves, an arrangement to neutralize said interfering waves comprising means to pick up energy

from the interfering source to produce balancing waves corresponding to the interfering wave, a phase controller and an amplitude controller for controlling the phase and amplitude of said balancing waves so that they may be impressed upon said transmission circuit equal in amplitude and opposite in phase to the interfering wave, and means automatically controlled by said interfering wave and said balancing waves to adjust said phase controller whenever said waves depart from their normal phase relation.

5. In combination with a transmission circuit subject to interfering waves, an arrangement to neutralize said interfering waves comprising means to pick up energy from the interfering source to produce balancing waves corresponding to the interfering wave, a phase controller and an amplitude controller for controlling the phase and amplitude of said balancing waves so that they may be impressed upon said transmission circuit equal in amplitude and opposite in phase to the interfering wave, and means automatically controlled by said interfering wave and said balancing wave for adjusting said amplitude controller whenever the amplitude of one of said waves becomes greater than the other.

6. In combination with a transmission circuit subject to interfering waves, an arrangement to neutralize said interfering waves comprising means to pick up energy from the interfering source to produce balancing waves corresponding to the interfering wave, a phase controller and an amplitude controller for controlling the phase and amplitude of said balancing waves so that they may be impressed upon said transmission circuit equal in amplitude and opposite in phase to the interfering wave, means automatically controlled by said interfering wave and said balancing waves to adjust said phase controller whenever said waves depart from their normal phase relation, and means automatically controlled by said interfering wave and said balancing waves to adjust said amplitude controller whenever the amplitude of one of said waves becomes greater than the other.

7. In combination with a transmission circuit subject to interfering waves, an arrangement to neutralize said interfering waves comprising means to pick up energy from the interfering source to produce balancing waves corresponding to the interfering wave, a phase controller and an amplitude controller for controlling the phase and amplitude of said balancing waves so that they may be impressed upon said transmission circuit equal in amplitude and opposite in phase to the interfering wave, a phase balancer controlled by said interfering wave and said balancing wave, a relay

controlled by said phase balancer, and circuits interconnecting said relay and phase balancer so that when said waves depart from their normal phase relation in one direction said relay will close one of its contacts and when said waves depart from their normal phase relation in another direction said relay will close another contact, and means controlled over said contacts for adjusting said phase controller to bring said waves into normal phase relation.

8. In combination with a transmission circuit subject to interfering waves, an arrangement to neutralize said interfering waves comprising means to pick up energy from the interfering source to produce balancing waves corresponding to the interfering wave, a phase controller and an amplitude controller for controlling the phase and amplitude of said balancing waves so that they may be impressed upon said transmission circuit equal in amplitude and opposite in phase to the interfering wave, an amplitude balancer controlled by said interfering wave and said balancing wave, a relay associated with said amplitude balancer, and circuits for said amplitude balancer and relay whereby when the amplitude of the balancing wave exceeds that of the interfering wave said relay will close one of its contacts, and when the amplitude of the interfering wave exceeds that of the balancing wave said relay will close another of its contacts, and means controlled over said contacts for adjusting said amplitude controller to bring both waves to the same amplitude.

9. In combination with a transmission circuit subject to interfering waves, an arrangement to neutralize said interfering waves comprising means to pick up energy from the interfering source to produce balancing waves corresponding to the interfering wave, a phase controller and an amplitude controller for controlling the phase and amplitude of said balancing waves so that they may be impressed upon said transmission circuit equal in amplitude and opposite in phase to the interfering wave, a phase balancer controlled by said interfering wave and said balancing wave, a relay controlled by said phase balancer and circuits interconnecting said relay and phase balancer so that when said waves depart from their normal phase relation in one direction said relay will close one of its contacts and when said waves depart from their normal phase relation in another direction said relay will close another contact, means controlled over said contacts for adjusting said phase controller to bring said waves into normal phase relation, an amplitude balancer controlled by said interfering wave and said balancing wave, a relay associated with said amplitude balancer and circuits for said ampli-

tude balancer and relay whereby when the amplitude of the balancing wave exceeds that of the interfering wave said relay will close one of its contacts and when the amplitude of the interfering wave exceeds that of the balancing wave said relay will close another of its contacts, and means controlled over said contacts for adjusting said amplitude controller to bring both waves to the same amplitude.

10. In combination with a transmission circuit subject to interfering waves, an arrangement to neutralize said interfering waves comprising means to pick up energy from the interfering source to produce balancing waves corresponding to the interfering wave, a phase controller and an amplitude controller for controlling the phase and amplitude of said balancing waves so that they may be impressed upon said transmission circuit equal in amplitude and opposite in phase to the interfering wave, a phase balancer controlled by said interfering wave and said balancing wave, said phase balancer comprising a pair of vacuum tubes, a polar relay having windings in the output circuits of said tubes, and means for impressing both said interfering wave and said balancing wave upon the circuits of both tubes in such phase relation that when said waves are in opposite phase relation upon said main transmission circuit no effect will be produced upon said relay but when said waves depart from their normal phase relation the effects upon the two tubes will be unbalanced and said relay will be actuated, and means controlled by said relay for adjusting said phase controller until said phase balancer is again balanced.

11. In combination with a transmission circuit subject to interfering waves, an arrangement to neutralize said interfering waves comprising means to pick up energy from the interfering source to produce balancing waves corresponding to the interfering wave, a phase controller and an amplitude controller for controlling the phase and amplitude of said balancing waves so that they may be impressed upon said transmission circuit equal in amplitude and opposite in phase to the interfering wave, an amplitude balancer controlled by said interfering wave and said balancing wave, said amplitude balancer comprising a pair of vacuum tube detectors, a polar relay having windings in the output circuits of said detectors, means to impress said balancing wave upon the circuit of one of said detectors, and means to impress the interfering wave upon the circuit of the other detector so that when both waves have the same amplitude no effect will be produced upon said polar relay and if the amplitude of one of the waves exceeds that of the other said polar relay will be actuated, and means con-

trolled by said polar relay for adjusting said amplitude controller to bring both waves again to the same amplitude.

12. In combination with a transmission circuit subject to interfering waves, an arrangement to neutralize said interfering waves comprising means to pick up energy from the interfering source to produce balancing waves corresponding to the interfering wave, a phase controller and an amplitude controller for controlling the phase and amplitude of said balancing waves so that they may be impressed upon said transmission circuit equal in amplitude and opposite in phase to the interfering wave, a phase balancer controlled by said interfering wave and said balancing wave, said phase balancer comprising a pair of vacuum tubes, a polar relay having windings in the output circuits of said tubes, and means for impressing both said interfering wave and said balancing wave upon the circuits of both tubes in such phase relation that when said waves are in opposite phase relation upon said main transmission circuit no effect will be produced upon said relay but when said waves depart from their normal phase rela-

tion the effects upon the two tubes will be unbalanced and said relay will be actuated, means controlled by said relay for adjusting said phase controller until said phase balancer is again balanced, an amplitude balancer controlled by said interfering wave and said balancing wave, said amplitude balancer comprising a pair of vacuum tube detectors, a polar relay having windings in the output circuits of said detectors, means to impress said balancing wave upon the circuit of one of said detectors, and means to impress the interfering wave upon the circuit of the other detector so that when both waves have the same amplitude no effect will be produced upon said polar relay and if the amplitude of one of the waves exceeds that of the other said polar relay will be actuated, and means controlled by said polar relay for adjusting said amplitude controller to bring both waves again to the same amplitude.

In testimony whereof, I have signed my name to this specification this 16th day of May, 1924.

LESTER M. ILGENFRITZ.
